(57) **CLAIM**

The ornamental design for a cycle, as shown and described.

DESCRIPTION

FIG. 1 is a top plan view of a cycle showing my new design;

FIG. 2 is an elevational right side view thereof;

FIG. 3 is an elevational left side view thereof;

FIG. 4 is an elevational back view thereof;

FIG. 5 is an elevational front view thereof;

FIG. 6 is a perspective view thereof;

FIG. 7 is a top plan view of a second embodiment of a cycle showing my new design;

FIG. 8 is an elevational left side view thereof;

FIG. 9 is an elevational right side view thereof;

FIG. 10 is an elevational front view thereof;

FIG. 11 is an elevational back view thereof;

FIG. 12 is a perspective view thereof;

FIG. 13 is a top plan view of a third embodiment of a cycle showing my new design;

FIG. 14 is an elevational left side view thereof;

FIG. 15 is an elevational right side view thereof;

FIG. 16 is an elevational back view thereof;

FIG. 17 is an elevational front view thereof;

FIG. 18 is a perspective view thereof;

FIG. 19 is a top plan view of a fourth embodiment of a cycle showing my new design;

FIG. 20 is an elevational left side view thereof;

FIG. 21 is an elevational right side view thereof;

FIG. 22 is an elevational front view thereof;

FIG. 23 is an elevational back view thereof; and,

FIG. 24 is a perspective view thereof.

The broken lines showing the wheels are for illustrative purposes only and form no part of the claimed design.
